UNITED STATES PATENT OFFICE

150,099

DESIGN FOR A GAME CHECK

Walter W. Taylor and Leo McMenemy,
Kansas City, Kans.

Application September 24, 1945, Serial No. 122,294

Term of patent 14 years
(Cl. D34—5)

To all whom it may concern:

Be it known that we, Walter W. Taylor and Leo McMenemy, citizens of the United States and both residing at Kansas City, in the county of Wyandotte and State of Kansas, have invented a new, original, and ornamental Design for a Game Check, of which the following is a specification, reference being had to the accompanying drawing, forming a part thereof.

Fig. 1 is a top plan view of the game check, showing our new design.

Fig. 2 is a bottom plan thereof; and
Fig. 3 is an edge elevational view thereof.

We claim:

The ornamental design for a game check, as shown.

WALTER W. TAYLOR.
LEO McMENEMY.
